CLAIM

See application file for complete search history.

The ornamental design for a terrestrial unit for connectivity to a balloon network, as shown and described.

DESCRIPTION

This application is also related to U.S. Patent Application Ser. No. 29/540,393 filed on Sept. 24, 2015. The entire disclosure contents of these applications are herewith incorporated by reference into the present application.

FIG. 1 is terrestrial unit for connectivity to a balloon network in a perspective view;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines represent portions of the terrestrial unit for connectivity to a balloon network that form no part of the claimed design.
